CLAIM

The ornamental design for a sterilizer for flexible cystoscope, as shown and described.

DESCRIPTION

FIG. 1 is a perspective view of a sterilizer for flexible cystoscope, showing my new design;

FIG. 2 is a right side elevational view, the opposite side elevational view being a mirror image thereof;

FIG. 3 is a top plan view thereof;

FIG. 4 is a front elevational view thereof;

FIG. 5 is a rear elevational view thereof; and,

FIG. 6 is a bottom plan view thereof;

The broken line showing in FIGS. 1-6 is for illustrative purposes only and forms no part of the claimed design.

FIG. 2

FIG. 3

FIG. 4

FIG. 5

FIG. 6
